Primary Examiner — Natasha Vujcic(74) *Attorney, Agent, or Firm* — Volpe Koenig**(57) CLAIM**

The ornamental design for a part of a compact air conditioner, as shown and described.

DESCRIPTION

FIG. 1 is a front perspective view of a part of a compact air conditioner in accordance with the present invention;

FIG. 2 is a front elevation of the design shown in FIG. 1;

FIG. 3 is a back elevation of the design shown in FIG. 1;

FIG. 4 is a left side elevation of the design shown in FIG. 1;

FIG. 5 is a right side elevation of the design shown in FIG. 1;

FIG. 6 is a top plan view of the design shown in FIG. 1; and,

FIG. 7 is a bottom plan view of the design shown in FIG. 1.

The broken lines depict portions of a compact air conditioner in which the design is embodied that form no part of the claimed design.

The dot-dash lines denote the boundary of the claim and form no part of the claimed design.

1 Claim, 7 Drawing Sheets(56)
